UNITED STATES PATENT OFFICE.

DE WITT C. BEANE, OF NEWARK, NEW JERSEY.

PIPE-THREADING DIE-STOCK.

SPECIFICATION forming part of Letters Patent No. 393,457, dated November 27, 1888.

Application filed July 6, 1888. Serial No. 279,193. (No model.)

To all whom it may concern:

Be it known that I, DE WITT C. BEANE, a citizen of the United States, residing at Newark, in the county of Essex and State of New Jersey, have invented certain new and useful Improvements in Pipe-Threading Die Stocks; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to secure a more convenient and ready adjustment, to reduce the cost of construction, and to otherwise provide a more durable and efficient pipe-stock.

The invention consists in the improved pipe-stock having the arrangements and combinations of parts substantially as will be herein-after set forth, and finally embodied in the clauses of the claim.

Referring to the accompanying drawings, in which like letters of reference indicate corresponding parts in each of the several figures, Figure 1 is a plan of the improved pipe-stock, showing an outer face portion of the die-holder removed. Fig. 2 is a side elevation of the same. Fig. 3 is a section taken through line *w* of Fig. 5, showing a certain stop pin adapted to engage a die-holder and keep the same from turning. Fig. 4 is a plan view of said stop pin. Fig. 5 is a sectional view taken 35 through line *x*, Fig. 1.

In said drawings, *a* indicates a bed-plate, having at the opposite ends thereof sockets *a'*, adapted to receive handles *b*, *b*, which extend oppositely, so as to allow both hands to be used 40 in turning the pipe stock. The center of the said bed plate is provided with large perforations considerably larger than the pipe upon which the screw is to be turned, and the upper face of the said plate is formed to receive a 45 top plate, *c*. The said top plate is recessed or chambered on the under side, as at *c'*, Fig. 5, the chamber *c'* being formed between the outer part of said plate and the said bed-plate. In 50 said chamber is arranged a double pawl, *d*, Fig. 1, and a spring, *e*, adapted to engage a ratchet, *h*, on the die-holder, as will be herein-after described. The upper face of the said

top plate is provided with a large annular opening, through which a die-holder, *f*, extends. The said die-holder *f* is shown more clearly in Fig. 5, where it is shown to rest upon the bed-plate *a* and held thereon by the said top plate, the ratcheted flange *h* lying between the said bed-plate and the top plate. At one side of the said ratcheted flange *h* is a shoulder, *g*, which has its bearings in the large opening in the bed-plate *a*. On the other side of the said flange is a shoulder, *i*, which lies in the large opening in the top plate, all as will be evident upon inspection of Fig. 5. At the center of the said holder is a pipe passage, *j*, through which the pipe, bolt, or shaft upon which the thread is cut extends.

u is a set-screw for steadyng the pipe-stock on the pipe, and *v* is a set-screw for a similar purpose when a bushing, *v'*, is used.

The upper end of the said passage *j* is enlarged to form a chamber, *K*, into which the chips or shavings from the pipe may fall.

Upon the upper side of the holder is formed a chamber, *n*, for the die or thread-cutter, the said chamber having a lateral passage or opening, *l*, through which the die to be inserted in the holder may be slipped into place. These guideways *o* are formed on two opposite sides 8c of the chamber *n*, as shown in Fig. 2, and extend longitudinally between the studs *m' m'*, as shown in Fig. 1, and extend upward to nearly the top of the chamber *n*, as shown in Fig. 5. These guideways are preferably made 85 integral with the studs *m' m'*. At one side of said passage is a stop, *m*, and at the sides of the chamber *n* are formed guideways or bars *o o*, which prevent the corners of the die from catching.

At the mouth or passage *l* is arranged a suitable catch, *p*, which may be controlled by a spring, but preferably by merely turning in its bearings, so that a lip, *r*, may engage the edge or side of the die when turned down, as shown in Fig. 5, to prevent the same from falling out. When it is desired to remove the die, this catch is turned up by means of a thumb-piece, *p'*, into a horizontal position, as shown in Fig. 1.

The receptacle or chamber *n* for the die is approximately of a shape corresponding with the die-plate, so that the plate cannot turn therein in the operation of cutting.

The facing *s* of the holder is permanent thereon or formed integral therewith, as may be desired, the said facing being preferably held on by studs *m m'* of the holder by rivets cast on the holder ends of said studs and extending into said facing and there being riveted.

To prevent the holder from turning in its bearings I have provided a stop pin or key, *t*, (shown more clearly in Figs. 3, 4, and 5,) which is adapted to engage the periphery of the shoulder *g* of the holder, which latter is suitably notched, countersunk, or recessed, as at *g'*, Fig. 3, to receive the end of the said pin.

The bed-plate *a* is provided with a chamber, *g²*, and a bearing, *g³*, and a slot, *g⁴*, Figs. 3 and 4. The said pin *t* extends through the chamber to enter the notch or recess *g'*, and is provided with a spring, *g⁵*, which engages the said shoulder *g³*, and a pintle or shoulder, *g⁶*, Fig. 3, whereby the said pin *t* is held normally into engagement with the die-holder. The said pin *t* may be held from such normal engagement by means of a pintle, *g⁷*, which extends from the pin *t*, as shown in Figs. 3 and 4.

By drawing on the pin *t* the pintle is caused to pass through the slot *g⁴*, and by turning the said pin *t* the said pintle is caused to engage the bearing *g³*, so that said pin is held away from the die-holder, as will be understood.

By the use of the spring actuated pin *t* and notched holder *f* said pin and holder may be brought into holding relation automatically, as may be required. This spring-actuated pin *t* is only used in what is known as "hand-over-hand cutting," or when the pipe stock is turned continually in one direction. In such cases the pawl-and-ratchet device is dispensed with. For general work I prefer the pawl-and-ratchet device and dispense with the pin *t*.

By having the facing *s* of the holder permanent with the opening *l* at the side and a simple catch, the die may be arranged in place in the holder very quickly and without the trouble incident to the use of a separate plate, such as have heretofore been employed.

To allow of the die and holder being used in cutting either a right or a left hand screw, I have provided a double pawl, *d*, having pawl-teeth *d' d'*, and a bearing, *d²*, to enter the spring *e*. The said pawl is also provided with a finger-piece, *d³*, which extends through the slot *d⁴* in the top plate, *c*, and thus the said pawl may be turned so that either of the teeth *d'* may thus be brought into engagement with the ratchet *h*.

The pawl and spring are held within the chamber *c'*, so that they are protected from accidental displacement or other injury, and the relation of the spring and pawl is such as that the said pawl may be changed in its relation to the ratchet without altering the position of the spring. To this end the spring

is arranged approximately at right angles to 65 the longitudinal line of the pipe-stock, and a bearing *d³* vibrates from one side to the other of said line, when the pawl-teeth *d'* are changed in their relations to the ratchet. The spring is also an independent and separate piece from 70 the pawl, so that the said pawl is readily changed without disturbing the spring. The spring *e* is intervened between the bearing *d²* of the pawl and the bearings *d⁵ d⁶* of the bed-plate or top plate.

The die to be used is slid into the die-chamber and the catch *p* is turned down, as shown in Fig. 5, thus holding the die in proper position in the die-chamber. The pipe to be cut is first firmly secured to a pipe vise or bench in the ordinary manner. The end of the pipe on which the screw-thread is to be cut is then passed through the opening *j* of the pipe-stock until it reaches the cutting-teeth on the inside of the die. The handle of the pipe-stock is 85 then moved up and down, causing the die, with its cutting teeth, to move in one direction around the pipe and cut the thread on the same, according to the number of cutting-teeth on the die.

Having thus described the invention, what I claim as new is—

1. In a pipe-stock, the combination of a bed-plate and a top plate with a die-holder, *f*, having ratchets *h*, a notch or recess, *g'*, and a spring-actuated holder, *t*, adapted to engage the said notch and hold the die holder in position automatically, substantially as and for the purposes set forth.

2. In a pipe-stock, the combination of a bed-plate, *a*, a top plate, *c*, a die-holder having a die receptacle, *n*, formed in the said holder and having a lateral passage, *l*, and a catch, *p*, to prevent withdrawal of the die-plate, substantially as and for the purposes set forth.

3. In a pipe-stock, the combination of a bed-plate and top plate, a ratcheted die-holder and a double pawl having a finger-piece, *d³*, and arranged in a chamber between said plates 110 a spring, *e*, substantially as and for the purposes set forth.

4. In a pipe-stock, the combination of a bed-plate, a ratcheted die-holder, and a pawl, the said die-holder being provided with a lateral passage, *l*, leading to the die receptacle or chamber, the said chamber having at the side opposite the passage *l* a stop, *m*, and at the other side suitable guides or ways, *o*, substantially as and for the purposes set forth.

In testimony that I claim the foregoing I have hereunto set my hand this 5th day of July, 1888.

DE WITT C. BEANE.
